(57) **CLAIM**

I claim the ornamental design for a T-handle, as shown and described.

DESCRIPTION

Cross-Reference to Related Application: T-Handle Assembly (U.S. Design patent application), Latch Housing (U.S. Design patent application).

FIG. 1 is a perspective view of a t-handle showing my new design;

FIG. 2 is a top plan view;

FIG. 3 is a bottom plan view thereof;

FIG. 4 is a rear elevational view thereof;

FIG. 5 is a front elevational view thereof; and,

FIG. 6 is a left side elevational view thereof, the right side elevational view being the same.

Those features depicted with dashed lines do not form a part of the disclosed design.
